UNITED STATES PATENT OFFICE.

WILLIAM JAY SMITH, OF SAN FRANCISCO, CALIFORNIA.

APPARATUS FOR THAWING EXPLOSIVES.

SPECIFICATION forming part of Letters Patent No. 635,945, dated October 31, 1899.

Application filed February 15, 1899. Serial No. 705,561. (No model.)

To all whom it may concern:

Be it known that I, WILLIAM JAY SMITH, a citizen of the United States, residing in the city and county of San Francisco, State of California, have invented certain new and useful Improvements in Apparatus for Thawing Explosives; and I do hereby declare the following to be a full, clear, and exact description of said invention, such as will enable others skilled in the art to which it most nearly appertains to make, use, and practice the same.

In cold weather high explosives, such as dynamite and nitroglycerin powders, become frozen and require to be thawed before using. This is usually done by placing the frozen explosives in the oven of a stove or in hot water, which often results in an explosion, owing to chemical change or overheating.

The object of my invention is to provide a portable apparatus in which such high explosives can be thawed with less danger of being exploded and which when properly handled will be a practical safe thawing apparatus; and it consists of an inner vessel contained within a larger outside vessel, so as to leave a space between them into which steam or hot water can be introduced for supplying the necessary heat. The frozen explosive is placed in the inner vessel and is thawed by the surrounding heat.

My invention relates to details of construction in connection with said apparatus by which it is rendered safe, convenient, and durable, all as hereinafter described.

Referring to the accompanying drawings, Figure 1 is an exterior view of the apparatus, taken in perspective, showing the top; and Fig. 2 is a vertical section in elevation showing the arrangement of the parts.

Let A represent the exterior vessel, which is shown in the drawings as being cylindrical in form; but it can be made square or of other shape.

B is the top or head, and C is the bottom, of the vessel. The top and bottom, it will be noticed, are each set and secured inside the vessel, so as to leave a chime d extending all around at both top and bottom. The chime at the bottom forms the base upon which the apparatus stands and is a protection against injury to the body of the vessel when moving

it around. The upper chime serves as a dish or pan, as hereinafter described.

The inner vessel E can be of any desired form and is secured and supported centrally within the vessel A. It is considerably smaller than the outside vessel, so that a space is left all around it. It is supported upon the bottom of the large or outside vessel by legs G G. It has a neck H extending upward from its top and through the top B of the exterior vessel which serves as a hand-hole through which the explosive is introduced into or removed from the vessel. This hand-hole or opening is closed by a cap or plug I. J is a short tube which passes through the head or top of the vessel A and communicates with the space between the two vessels, and this tube or opening has also a cap or plug K adapted to close its upper end. On the opposite side of the hand-hole is another small opening L, which is also adapted to be closed by a plug or cap, as shown.

In the side of the outer vessel A a thermometer O is secured, as shown at Fig. 1, so that it forms a part of the apparatus.

The frozen dynamite or other explosive is introduced into the inner vessel E through the hand-hole opening, and the cap or plug I is then secured in place, so as to close the opening. Hot water or steam is then introduced into the space between the two vessels through the tube J. The chime d at the top of the vessel forms a pan, which will catch any overflow of water when hot water is used, and holes p are made in the chime at a point lower than the projecting tops of the openings, so that the overflow-water will be carried off through the waste-holes before it rises high enough to enter the openings. The frozen explosive is thus surrounded with a heated element without coming in contact with it and is readily thawed. When the interior water becomes cool, it can be discharged from the vessel through the orifice or opening L.

If steam is used, a steam-pipe can be connected from a boiler with the tube J and the orifices all closed, so as to surround the inner vessel with steam instead of hot water. The thermometer O will always indicate the inside temperature of the apparatus, so that the danger-point can be controlled.

This apparatus is portable and can be moved from place to place and provides a safe and reliable means for thawing such dangerous compounds.

5 Having thus described my invention, what I claim, and desire to secure by Letters Patent, is—

In a thawing apparatus, the combination of an outer tank, an inner tank, the walls of the tanks being spaced apart to form a chamber around the inner tank, the outer tank being provided with a chime at its upper end

having openings, and with a head having an opening for the passage which communicates with the inner tank, and with an inlet and 15 an outlet for the heating medium, the said passage inlet and outlet extending above the openings in the chime.

In witness whereof I have hereunto set my hand this 7th day of February, 1899.

WM. JAY SMITH.
